(57) **CLAIM**

The ornamental design for a furniture corner and edge configuration, as shown and described.

DESCRIPTION

FIG. 1 is a top left perspective view of a furniture corner and edge configuration showing my new design;

FIG. 2 is a top plan view thereof;

FIG. 3 is a right side elevational view thereof; and,

FIG. 4 is a top front perspective view, illustrating the furniture corner and edge configuration in a representative position on a desk thereof.

The broken lines depicting additional furniture portions in FIG. 4 represent environmental elements only and form no part of the claimed design. The underside of the furniture corner and edge configuration not shown forms no part of the claimed design.

1 Claim, 4 Drawing Sheets
